UNITED STATES PATENT OFFICE.

WOLFGANG BÄSELER, OF MUNICH, GERMANY, ASSIGNEE TO LORENZ-ZEISS-ZUGSICHERUNGS-G. M. B. H., OF BERLIN-TEMPELHOF, GERMANY.

TRAIN-CONTROLLING MEANS BY LIGHT RAYS.

Original application filed February 12, 1927, Serial No. 167,759, and in Germany February 16, 1927.
Divided and this application filed January 9, 1928. Serial No. 245,389.

This invention relates to an apparatus for the automatic control of trains by means of light rays and has more particularly for its object to provide a train control system for 5 automatically stopping a locomotive of a railroad in case it is passing a block signal which has been set against such passage of the train by a nearby rail signal station, under danger conditions, or for producing 10 only an optical or acoustic alarm signal on the locomotive in the event of the engineman's disregarding a danger stop signal.

The present application is a division of my copending application, Serial No. 167,759, 15 filed Febr. 12th 1927.

Another object of my invention is to provide means selectively responsive with respect to different points of the track in order to produce different effects at such points 20 such as e. g. to sound an alarm signal to remind the engineman of the approach to a block signal and then, in the event of the engineman's disregarding this alarm signal to apply the brakes automatically and bring 25 the train to a predetermined speed or to complete rest, or for the limitation of the train's speed by automatically applying the brakes in successive stages at predetermined successive points on the track lying within a given 30 braking stretch and thus to cause the train to be brought to rest at a point just to the rear of the entrance to the occupied block, irrespective of the speed at which the train is travelling and provided only the block remains occupied as long as the train is passing 35 this braking stretch, whereas in the event of the blocks becoming free during the train's passing the braking stretch the actuating devices are to become ineffective avoiding 40 thus an unnecessary braking or stopping of the train.

My invention relates to a controlling apparatus which makes particular use of the electrical properties of the well-known photo-electric cells under various light intensities 45 such as those consisting essentially of the metal selenium. These photo-electric cells have the peculiar characteristic of varying their electrical resistance under various light 50 intensities. Of these properties I make use and I apply them to the improvements hereinafter more fully set forth, presenting for this object a method and apparatus which will accomplish the purpose with the cer-

tainty and reliability needed in practical rail-road service.

Another object of my invention is to provide means for the limitation of the train's speed, if a predetermined speed is exceeded over particular parts of the track such as 60 when passing bridges, curves or like passages.

The salient principles of my invention consist in the fact that I provide in combination a source of light placed on the vehicle or locomotive, a light sensitive element arranged 65 on the locomotive in proximity to that source of light, and a reflecting member or mirror arranged fixedly on the track adjacent to a block signal and serving as an actuating means for causing the establishment of a 70 signalling or controlling action on the locomotive. This reflecting mirror represents the main feature of my invention and is of a novel and most efficient type to fulfill the requirements of the system in question. It is a 75 so-called "triple" mirror and consists essentially of three reflecting planes two of them being arranged rectangularly with respect to each other and the third one being arranged differing from this rectangular position. Such a "triple" mirror has the property with 80 respect to incoming light rays not to reflect in parallel direction, but to divide and reflect the incoming parallel rays of an aigrette in two symmetric aigrettes of rays. By the use 85 of a triple mirror as explained I ensure, even with considerable speeds of the train that the light sensitive cell on the locomotive is influenced a sufficiently long period of time by the light rays radiated by the source of 90 light on the locomotive to the reflecting mirror on the track and thrown back again by the same to the locomotive to hit upon the light sensitive element whatever their incoming direction may be.

My invention, as just outlined presents 95 essential advantages in that special sources of light for the transmission of signals are dispensed with, it being only necessary to arrange a source of light on the locomotive. Therefore, the operating costs and costs of 100 surveillance are kept low and existing signal lights on the track are not hampered by the addition of new ones.

In order to obtain the aforesaid selective 105 actions at different points on the track I may employ, too, triple mirrors at the different points having another angle of inclination of

one of its planes with respect to the other ones which are placed at right angles with respect to each other or as I may call it by using triple mirrors having different "orientation". Thus, each one of said mirrors has the property of reflecting incoming light waves irrespective of their incoming direction at a constant angle, to this incoming direction, this angle being dependent only 10 on the "orientation" of each individual mirror. Then, by positioning the single light sensitive cells pertaining to each one of the mirrors in a proper position with respect to each other and to the light source the effect 15 will be obtained that each cell will be struck only by rays coming from a distinct direction which may be adjusted as being that of the "orientation" of an individual mirror.

According to another feature of my invention 20 I may render the light rays re-selective by varying their intensity periodically or modulating them in accordance with a sine variation such as when employing an A. C. supplying an incandescent lamp and by using receiving devices responsive to such particular periodicity.

In order that my invention will be more 25 fully understood the following detailed description may be taken, reference being had 30 to the accompanying drawings in which:

Figure 1 is a schematic view illustrating the salient principles of the working details of my invention.

Figure 2 represents schematically the 35 structure of a "triple" mirror such as is used in the apparatus of my invention.

Figure 3 represents schematically the division of a light ray by a "triple" mirror such as is used in the apparatus of my invention.

Figures 4-6 are illustrative of an arrangement for successively reducing the train's speed, getting selective actions by employing differently "orientated" mirrors.

Referring more particularly to Figure 1 of 45 the drawing the numeral 1 designates the track, and 2 the locomotive to which is rigidly secured a box 3 containing an incandescent lamp 4 as a source of light. At the top 50 of the box 3 is secured a lens 5 projecting a beam of light to a triple mirror 6 secured rigidly on a bracket 7 which is supported by a pole 8 erected at the side of the track adjacent to a blocked section. A protecting cover 9 is placed in front of the mirror to 55 prevent exterior disturbances from reaching the mirror planes.

At the sides of the box 3 in proximity to the lamp 4 or the lens 5 is placed a light sensitive element 10. When the locomotive 60 is passing the signal pole 8, light rays radiated by the incandescent lamp 4 are reflected in the same direction as that in which they reach the mirror 6 provided the mirror planes are arranged at right angles with respect to 65 each other, and thereby hit upon the light

sensitive element 10 which by the variation of its electrical resistance operates a relay of a local circuit, which relay introduces the execution of the action required e. g. sounds an alarm bell or actuates the brakes, in a 70 manner commonly known in the art and not further described as being without the scope of the invention.

Figure 2 shows schematically the structure 75 of the reflecting mirror as employed in the arrangement of my invention. 11, 12, 13 are three reflecting planes. If one of the corners between the planes is not a right angle the incoming beam of a light ray (14) following on one of the planes 13 e. g. is reflected and divided in two symmetric rays as shown by the numerals 15' and 15" in the drawing.

Thus, referring to Figure 3 where 4 designates the source of light and 6 a triple 85 mirror a ray 14 sent out by the source of light perpendicularly to the mirror 6 will be reflected into itself in the case the three mirror planes are at right angles to each other, but it will be reflected to points 34 and 35 90 lying symmetrically with respect to the source of light in the case one angle of the planes of the mirror is displaced from its rectangular position.

The dimension of the angle (α) between 95 the incoming and outgoing rays is determined by the displacing of the two planes 11, 12 e. g. from their rectangular position.

Referring now more particularly to Figures 4-6 of the drawings which are illustrative of a system for producing selective actions at different points on the track, four reflecting mirrors 16, 17, 18 and 19 are arranged at successive distances along the track, e. g. of 150 m. from each other. A 100 designates an alarm stop signal and M the main block signal, their distance apart being 700 105 m., and it is required, in the event of the block being occupied that the train be brought to rest just to the rear of the block signal irrespective of the speed with which it is travelling. The mirror 16 is placed at 250 m. distance beyond the alarm stop signal A and 450 m. before the main block signal M, the second mirror 17 is placed 300 m., the third 110 mirror 18 is at 150 m. distance from the main block signal and the fourth mirror 19 is 115 arranged in close proximity to the main block signal M.

According to this novel feature of the 120 invention I employ several mirrors differently "orientated" so that the points of light reflected by them lie at the circumference of a circle and I place one of these mirrors at each one of the influencing points 16-19 according 125 to Figure 4. In Figure 5 the light points reflected by four of such differently orientated mirrors are shown as displaced at an angular distance of 45° one from another. Each two 130 symmetrical points 20, 20', 21, 21', 22, 22',

23, 23' belong together and are illuminated by one mirror having a distinct orientation. The light sensitive elements are arranged at the points 20, 21, 22, 23 with respect to the light source 4 so that each one will only be influenced by a beam of light coming from a particular direction on being illuminated by one of the differently orientated mirrors.

According to Figure 6 the numeral 36 designates a centrifugal speed device driven from an axle of the locomotive and having an indicating hand 37 of electrically conductive material which moves upon a disc having four contact segments 24-27 separated by insulating segments. Each of the contact segments 24-27 is conductively connected to one pole of a receiver (light sensitive element) 28, 29, 30, 31, respectively, the other poles of the receivers being connected to one terminal 39 of a local battery 38. The other battery terminal is connected in series with the winding 32 of a relay 33 and with the hand 37 of the centrifugal speed device 36. The armature 39 of the relay 33 controls an electrical circuit operating the brakes of the train in a manner well known in the art. The contact segments are so designed that the hand 37 moves on segment 27 as the train has a speed less than 25 km. per hour, on segment 26 as long as the speed is between 50 and 25 km. p. h. and on segment 25 as long as the speed is between 50 and 70 km. p. h. and on segment 24 when the speed exceeds 70 km. p. h. corresponding to the predetermined maximum speeds attributed to the points 16-19 of the track as shown in Figure 4, whereby one of the receivers 28-31 is successively included in the circuit of battery 38 according to the speed existing.

40 By varying the length of the contacting sectors 24-27 an adjustment for different categories of trains such as express trains, goods trains, etc., may be carried out. A further improvement may be incorporated with the arrangement just explained in that the circuits closed by the contacting segments of the contact disc and consequently the relay are rendered ineffective in case the engine driver has operated the brakes himself.

50 Instead of having the hand 37 of the centrifugal speed device 36 according to Figure 6 moving along the contact disc 24-27 in order to render effective each receiving circuit successively in accordance with one individual range of speed, the terminals of the receivers connected to the contact disc segments may be connected to the other terminal of the battery 38 in series with the winding of the relay 33 and the centrifugal speed device 36 may turn a covering disc 40 as shown by Figure 5 which covers one or more of the receivers 20-23 according to the speed of the train. In order to have distinct light points at the receiving point 20-23 and not having the light rays intended to influence one re-

ceiver to overlap with those intended to act upon the neighboring receiver collecting lenses may be arranged in front of the mirrors in order to concentrate the rays into a narrow beam. I do not desire to limit myself to the particular construction and arrangement of parts shown and described, but aim in the appended claims to cover all modifications which are within the spirit and scope of my invention.

What I claim as new and desire to secure by Letters Patent of the United States is:

1. In an automatic train control system of the character described, the combination of electromechanical locomotive control means of the train brakes including a light-influenced element and actuatable only when said element is influenced by the action of light, a light source arranged on the locomotive, a light-reflecting member having three reflecting planes positioned in a distinct angle relationship with respect to each other and adapted to reflect incoming light rays at a constant angle with respect to this incoming direction, said reflecting member being fixedly arranged on the track adjacent to a danger section or occupied block of a railway and being in its operative position under danger conditions to reflect light rays radiated by said light source on the locomotive in such a direction as to act upon said light influenced element.

2. In an automatic train control system of the character described, the combination of electric-mechanical locomotive control means of the train brakes including a plurality of light-influenced elements arranged in predetermined positions with respect to each other and to a light source, said control means being actuatable only when one of said elements is influenced by the action of light, light reflecting members being fixedly arranged at predetermined distances on the track adjacent with respect to a danger section or an occupied block of a railway and being in their operative position under danger conditions, each of these reflecting members having three reflecting planes and adapted to reflect incoming light rays at a constant angle, this constant angle being different for each of said reflecting members by positioning said planes in a proper angle relationship, to reflect light rays radiated by said light source on the locomotive in such a direction as to act upon one of said light-influenced elements, positioned accordingly with respect to said light source, and means for selectively rendering operative said light influenced elements in accordance with different ranges of the speed of the train.

3. In an automatic train control system of the character described, the combination of electric-mechanical locomotive control means of the train brakes including a plurality of light-influenced elements arranged in prede-

terminated positions with respect to each other and to a light source, said control means being actuatable only when one of said elements is influenced by the action of light, light reflecting members being fixedly arranged at predetermined distances on the track adjacent to a danger section or an occupied block of a railway and being in their operative position under danger condition, each of these reflecting members having three reflecting planes and adapted to reflect incoming light rays at a constant angle, this constant angle being different for each of said reflecting

members by positioning said planes in a proper angle relationship, to reflect light rays radiated by said light source on the locomotive in such a direction as to act upon one of said light-influenced elements positioned accordingly with respect to said light source, and a centrifugal speed device adapted to associate successively said light-influenced elements with said locomotive control means in accordance with different ranges of the speed of the train. 15 20

WOLFGANG BÄSELER.
